DESIGN FOR A JEWELRY CLIP

Maximilian C. Meyer, Brooklyn, N. Y.

Application May 30, 1942, Serial No. 107,059

Term of patent 7 years

To all whom it may concern:

Be it known that I, Maximilian C. Meyer, a citizen of the United States, residing at Brooklyn, in the county of Kings and State of New York, have invented a new, original, and ornamental Design for a Jewelry Clip, of which the following is a specification, reference being had to the accompanying drawing, forming a part thereof.

The dominant feature of the design resides in the portion of the jewelry clip shown in full lines.

I claim:

The ornamental design for a jewelry clip, substantially as shown and described.

MAXIMILIAN C. MEYER.
